UNITED STATES PATENT OFFICE.

FREDERICK J. ENGLE, OF SOUTH OMAHA, NEBRASKA.

FILLING-MACHINE.

1,253,018.

Specification of Letters Patent.

Patented Jan. 8, 1918.

Application filed August 13, 1915. Serial No. 45,418.

To all whom it may concern:

Be it known that I, FREDERICK J. ENGLE, a citizen of the United States, residing at South Omaha, in the county of Douglas and State of Nebraska, have invented new and useful Improvements in Filling-Machines, of which the following is a specification.

This invention relates to improvements in machines for filling cans or other receptacles with predetermined or measured charges of a commodity, proposing more particularly an improvement upon the broad or general type of machine which is disclosed in my prior U. S. Patent No. 998,230, granted May 23, 1911.

The type of machine referred to is saliently characterized by a revoluble material-containing receptacle provided with charge-measuring and discharging means; by means for holding the cans to be filled in relation to said receptacle; and by devices operable at a period of the movement of said receptacle for effecting the discharge of measured charges of the material into the cans.

The principal objects of the present invention are to provide a machine having the structural features stated which shall be materially simpler in its details of structure and organization than the machine disclosed in my said prior patent.

The above and other objects and advantages will appear as the description proceeds.

An embodiment of the invention is illustrated in the accompanying drawings, wherein—

Figure 1 is a plan view, mainly diagrammatic, showing the relation of the can-filling apparatus and can-sealing apparatus and the elements by which these apparatuses are coördinated;

Fig. 2 is an enlarged detail side elevation of the can-filling apparatus;

Fig. 3 is a plan view thereof with certain parts shown in section;

Fig. 4 is a detail vertical sectional view of the can-filling apparatus;

Fig. 5 is a detail perspective view of one of the charge-measuring and depositing devices;

Fig. 6 is a detail horizontal sectional view of the same;

Fig. 7 is a detail perspective view showing the devices employed for guiding the filled cans upon the conveyer by which said

cans are transferred to the sealing-mechanism.

Similar characters designate corresponding parts throughout the several views.

In the accompanying drawings I have shown a machine which is capable of handling materials of different kinds. That form of the invention, however, is particularly adapted to fulfil the requirements of a filling machine for depositing measured quantities of powdery substances into cans or receptacles. It will be understood, however, that the embodiment of the invention herein disclosed is given essentially as an example and that modifications and changes may be made in the construction and arrangement of the parts whereby the invention may be applied or adapted to the best advantage according to the circumstances and needs of each particular case. The substance with which the cans are to be filled is contained in a revoluble reservoir 1 shaped in cross-section to provide an annular trough as indicated in Fig. 4 and mounted upon a centrally located upright shaft 2 by which it is revolved. The reservoir 1 supports from its under side, by means of hangers 3, an annular shelf or platform 4, upon which the cans to be filled are disposed.

The bottom of the reservoir 1 is provided at appropriate intervals with charge-measuring and depositing devices, the details of which are shown in Figs. 4 and 5. These devices consist essentially of a hollow frustoconical member 5 having an attachment flange 6 for attachment to the bottom of the reservoir 1 and having its lower end controlled by a valve or closure plate 7. In the embodiment shown the valve or closure 7 is pivotally mounted, being carried by a pintle 8 journaled in ears 9 arranged at one side of the member 5. The valves 7, when in their normal closed position are held against the lower edges of the members 5 by springs 10, arranged on the pintles 8. The valves 7 are opened at a period of the rotation of the reservoir 1 and for this purpose each valve

has a lever arm 11 projecting beyond the pintle 8 and carrying a friction roller 12 which engages with a cam bar 13 extending preferably throughout one-third of a circle. The valves 7 are normally closed by springs 14 connected to the lever arms 11 and to the hangers 3 or parts carried by said hangers.

During the period when the valves 7 are 110

open and the charges of material are being discharged from the members 5 the upper ends of said members are maintained closed, the means employed conveniently consisting of a plate 14 stationarily supported within the reservoir 1, for example by hangers 15 secured to a stationary support 16 arranged above said trough.

The charges of material which are discharged from the members 5 are directed into the cans arranged on a ledge or platform 4 by hoppers 17 which are carried by the reservoir 1 and project downwardly therefrom, each hopper inclosing a member 5 and having a slot 18 which permits of the requisite movement of the valve 7.

To insure of the alinement of the cans with the hoppers 17 a generally annular frame 19 is employed, which said frame is suitably supported from the hangers 3 of the ledge or platform 4 and is provided at intervals corresponding to the intervals of the hopper 17 and in alinement with said hoppers, with depressions 20. The depressions 20 have at one end thereof a portion 20^a conforming to the outline or curvature of the can and beyond said portion 20^a they are of straight extent as at 20^b, the portions 20^b of the depression 20 extending to the outer circumference of the frame 19.

The can-filling apparatus is preferably arranged at one end of a table 21 and a can-sealing apparatus, designated generally as 22, may be arranged at the other end of said table in which case the filled cans are passed from the filling apparatus to the sealing apparatus by a conveyer 23 arranged longitudinally at one side of the table 21 and extending tangentially from the annular path of movement of the rotating elements of the can-filling apparatus. A can-feeding mechanism 24 of any suitable construction, and shown merely diagrammatically in the drawings, is arranged at the opposite side 45 of the table 21 and approximately half a circle distant from the point at which the conveyer 23 adjoins the can-filling apparatus.

As the reservoir 1 rotates the cans are successively fed to the ledge or platform 4 and into the depressions 20 of the frame 19 by the can-feeding apparatus 24. During the movement of the cans between the can-feeding apparatus 24 and the conveyer 23 the valves 7 are opened by the stationary cam 13, whereby the charges of material in the members 5 are deposited in the cans, the valves 7 being held open for a sufficiently long period to insure that the entire charge 60 shall pass from each member 5 into the can in registry therewith. During the period in which the valves 7 are held open by the cam 13, the upper ends of the members 5 are closed by the plate 14, the latter being substantially co-extensive with the cam 13.

Shortly prior to the passage of the members 5 from the plate 14 the valves 7 pass beyond the cam 13 and are closed by their springs 7*. Thereafter the members 5 pass from under the plate 14 and new charges of the material flow into the said members from the reservoir 1 and during the continued revolution of said reservoir are supported upon the valves 7 until the period is reached during which said valves are moved to open 75 position.

The conveyer 23 to which reference has been made may be of any construction suitable for the purposes in view, but it is preferably an endless conveyer and, as such, is shown merely diagrammatically in the drawings. An operative connection between the upper stretch of the conveyer 23 and the platform 4 is established by an intermediate shelf 25 (Figs. 1 and 7) having at one end 80 an edge adjoining and conforming to the platform 4 and having its other end overhanging or immediately adjoining the upper stretch of the conveyer 23. The shelf 25 extends tangentially from the platform 90 4 and carries a pair of parallel guide bars 26 and 27, the latter extending under the frame 19 (Fig. 3) and serving to engage each can successively brought into relation thereto and to guide the same upon the shelf 95 25. Obviously each can that is moved upon the shelf 25 acts as a follower upon the can in advance thereof on said shelf, whereby the cans are pushed in step by step fashion from the shelf 25 upon the conveyer 23. 100

During the movement of the cans between the can filling apparatus and the sealing apparatus the can tops are deposited or imposed upon the can bodies by any suitable means (not shown) and the cans are thereupon ready for the action of the sealing mechanism. 105

The can-sealing mechanism which, *per se*, forms no part of the present invention, is preferably of an improved construction which is shown in a general way in Fig. 1 and comprises a rotatable cylindrical drum 28 arranged in concentric relation within a wall 29 of annular outline and provided at its lower end with a circumscribing can-supporting ledge or platform 30. The drum 28 is mounted upon and rotated by a centrally arranged upright shaft 39. The previously applied can tops are positively and securely fixed to the can body by the coaction of the forming ribs 31 and 32 provided upon the drum 28 and annular wall 29 respectively and having their cross-sections selected to suitably crimp the can top and the adjoining portion of the can body and to thereby establish an interlocked relation between these elements. 115 120 125

The annular wall 29 is interrupted to provide for the passage of the cans into the annular space between the same and the drum 130.

28 and to provide for the discharge of the cans from said space. The can-sealing mechanism is arranged at one side of the conveyer 23, and it is therefore necessary to 5 provide means for transferring the cans from the conveyer 23 to the can-sealing mechanism. This means is preferably of the construction shown in the drawings and, as shown, consists of a pair of vertical guide 10 walls 33 which at one end thereof overhang the conveyer 23 and which for an initial portion of their length extend at an angle from said conveyer. At one side of the conveyer 23 the walls 33 support a bottom plate 34 15 upon which the cans are advanced from said conveyer. Beyond the bottom plate 34 the walls 33 are bent at an angle, as at 33^a, in concentric relation to a revolving transfer table 35, which forms a continuation of the 20 plate 34 and which transfers the cans from the plate 34 to a similar plate 36, the latter extending from the table 35 to the ledge or platform 30 which circumscribes the lower end of the drum 28. The cans are directed 25 from the can-sealing mechanism by a pair of vertical walls 37 provided with a bottom plate 38 adjoining and extending from the ledge or platform 30.

During the movement of the conveyer 23 30 the cans will be deflected by the bars 33 upon the plate 34 and each can so deflected will act as a follower upon the can or cans in advance thereof and will push the same through a distance equal to its diameter. 35 Thus the ejecting power of the conveyer 23 is used to effect the transfer of the cans from said conveyer to the can-sealing mechanism, this being possible by the reduction of friction due to the free revolution of the table 40 35 and to the concentric relation of said table and the angular portion 33^a of the walls 33.

Any approved means may be employed to 45 operate the can-filling apparatus and the can-sealing mechanism. For example, and as shown in Fig. 1, the upright shafts 2 and 39 are connected by bevel gearing 40 with longitudinal drive shafts 41 and 42 geared by belt gearing 43 to a line shaft or motor 50 shaft (not shown). The gearing 43, in each instance, includes as a part thereof a suitable clutch mechanism 44, by which the respective shafts 41 and 42 may be put into or out of relation with the source of driving power. 5 The clutches 44 are conveniently controlled 55 by levers 45 arranged at the end of the table 21. By virtue of the clutches 44 it is possible to operate the can-filling mechanism independently of the sealing mechanism or to 60 operate the can sealing mechanism independently of the filling mechanism, or to operate both simultaneously, as in the manner above described. Where the can-filling mechanism is operated independently of the sealing mechanism the walls 33 may, if desired,

be temporarily removed and the cans may be taken from the conveyer 23 in any suitable manner.

The conveyer 23, as also revolving table 35, may or may not be positively driven. It 70 is practical for these elements to run free, as shown in the drawings, in which case the conveyer will have a step by step operation and all the power for effecting the transfer of the cans from the can-filling apparatus to the can-sealing apparatus will be developed from the ejecting power of the can-filling apparatus. In this way the construction of the machine as regards the correlation of the filling apparatus and sealing apparatus is 75 rendered exceedingly simple and its operation in this regard is highly efficient and economical.

Having fully described my invention, I claim—

1. In a can filling apparatus, in combination, a revolving reservoir, an annular can platform or ledge revoluble therewith, a plurality of discharge members projecting from said reservoir, spring closed valves 90 normally closing the discharge ends of said members and movable horizontally across said discharge ends, and a fixed arcuate cam bar arranged below said reservoir and extending through a fraction of a circle, said 95 valves having horizontal lever arms for engagement with said cam bar and being opened in consequence of such engagement.

2. In a can filling apparatus, in combination, a revolving reservoir, a plurality of discharge members projecting from said reservoir, valves normally closing the discharge ends of said members and movable horizontally across said discharge ends, and a hopper inclosing each discharge member 100 105 and having a horizontal slot through which the valve of said member is movable.

3. In a can filling apparatus, in combination, a revolving reservoir, an annular can platform or ledge, hangers supporting said platform or ledge from and below said reservoir, a plurality of discharge members projecting from said reservoir, valves normally closing said discharge members, and horizontally movable across their discharge 110 115 ends, said valves having lever arms, springs connected to said lever arms and to said hangers and acting to hold said valves closed and a fixed arcuate cam bar arranged below said reservoir and extending through a fraction of a circle for engagement with 120 said lever arms to effect the opening of said valves.

4. In a can filling apparatus, in combination, a revolving reservoir, an annular can platform or ledge, hangers supporting said platform or ledge from and below said reservoir, a plurality of discharge members projecting from said reservoir, valves normally closing said discharge members, 125 130

5 springs connected to said hangers and acting to hold said valves closed, and an annular frame arranged above said platform or ledge and secured to said hangers, said frame having can receiving depressions.

5. In a can filling apparatus, in combination, a revolving reservoir, an annular can platform or ledge revoluble therewith, a plurality of discharge members projecting from said reservoir, valves having pivotal supports externally of said discharge members and movable horizontally across the ends of said discharge members, said valves having springs which effect their normal closure and having horizontal lever arms beyond their pivots and a fixed arcuate cam bar arranged below said reservoir and extending through a fraction of a circle for engagement with said lever arms to effect the opening of said valves.

6. In a can filling apparatus, in combination, a revolving reservoir, an annular can platform or ledge revoluble therewith, a

plurality of discharge members projecting from said reservoir, valves having pivotal supports externally of said discharge members and movable horizontally across the ends of said discharge members, said valves having springs which effect their normal closure and having horizontal lever arms beyond their pivots, a fixed arcuate cam bar arranged below said reservoir and extending through a fraction of a circle for engagement with said lever arms to effect the opening of said valves, and a hopper inclosing each discharge member and having a horizontal slot through which the valve of said member is movable.

In testimony whereof I have hereunto set my hand in presence of two subscribing witnesses.

FREDERICK J. ENGLE.
